UNITED STATES PATENT OFFICE

109,804

DESIGN FOR A BRACELET OR SIMILAR ARTICLE

William W. Hobe, New York, N. Y.

Application April 25, 1938, Serial No. 76,735

Term of patent 3½ years

To all whom it may concern:

Be it known that I, William W. Hobe, a citizen of the United States of America, residing in New York city, in the Borough of Manhattan, county and State of New York, have invented a new, original, and ornamental Design for a Bracelet or Similar Article, of which the following is a specification, reference being had to the accompanying drawing, forming part thereof, wherein,

The figure is a perspective view of a bracelet or similar article, showing my new design.

I claim:

The ornamental design for a bracelet or similar article, substantially as shown.

WILLIAM W. HOBE.
